SHIRT COLLAR

Heinz Henschel, Johannesburg, Transvaal, Union of South Africa, assignor of one-half to Heinz Bernhard Hammerschlag, Johannesburg, Transvaal, Union of South Africa

Application February 8, 1945, Serial No. 576,729
In the Union of South Africa March 21, 1944

2 Claims. (Cl. 2-139)

1

This invention relates to shirt collars, and more particularly to turn-down collars and the means for attaching them to their shirts.

The object of the invention is to provide a turn-down collar having its normally exposed portion easily replaceable while it is secured to the shirt in such a manner that it can be worn and laundered without removal from the shirt.

Normally a turn-down collar is either attached to the neckband of a shirt by two studs one in front and one at the back or it is permanently fastened by means of stitching to the neckband. The permanently fastened collar is more comfortable to wear; it can be worn without a tie as an open-neck shirt, it is also more convenient because it is laundered with the shirt. Owing to the fact that the greatest wear on a shirt occurs around the top of the collar the detachable collar is popular and usually two collars are supplied with each shirt. Each collar is usually made from two thicknesses of the shirting material with a stiffening insertion between the thicknesses. The collar is made wide enough to be folded in half and so becomes a "turn-down" collar. The inside up-standing portion is attached to the neckband and the turn-down portion folds over and covers the necktie except where it is tied in front of the collar. In this invention the turn-down collar is made in two portions. The upright inner portion and the turn-down outer portion including the top of the collar where the greatest wear occurs.

The invention is illustrated in the accompanying drawing in which

Fig. 1 shows the upper portion of a shirt with the collar according to this invention in place but with one end upturned.

Fig. 2 shows the shirt with the outer portion of the collar removed.

Fig. 3 shows a portion of Fig. 1 but with the parts partially disconnected.

Fig. 4 shows a portion of a spare collar.

Fig. 5 is a sectional view taken approximately on the line 5-5 of Fig. 1.

According to this invention, and as shown in the drawing, the collar 1 consists of the upright inner portion 2 and the turn-down outer portion 3 with a fold at 4 providing an inner rim 5. This inner downwardly projecting rim 5 is removably attached to the top of the upright portion 2. The attachment is made in such a manner that the shirt and collar can be worn and laundered as comfortably and easily as if the collar was permanently attached to the shirt. At the same time, while the inner or upright portion 2 of the collar

2

1 remains permanently attached to the shirt, two or more of the turn down portions 3 are supplied with the shirt and when one is worn it can be removed and replaced with a spare one by the use of this invention. A simple lacing process is all that is required for such replacement, that is there is no necessity of having recourse to machine or hand sewing.

The upright portion 2 of the collar is made of two thicknesses 6, 7, of the shirting material with, if desired, the stiffening material 8 between them. The edge 9 of the neck opening of the shirt is placed between the hemmed edges of 6 and 7 and the parts stitched together. This permanently fastens the upright portion 2 to the shirt.

The top 10 of the upright portion 2 is made double. The inner portion, that is the part towards the inside of the shirt, and exposed to view, has a plain unbroken surface. Turned down and inside this top edge 10 is a lining 11 as shown and outside of that again is a ring or flap 12 so that between 11 and 12 a channel 13 is formed. 11 and 12 are perforated with lace holes 14, 15 respectively and regularly spaced and placed opposite one another.

The channel 13 is made suitable in depth to accommodate the inner folded down rim 5 of the turned-down portion of the collar 3. This rim 5 is provided with lace holes 16 similarly placed in relation to lace holes 14, 15 in 11 and 12.

The collar is suitably shaped particularly where the ends 17 meet. At one end 17 (as shown on the right hand in the drawing) is attached the end 18 of a lace 19. This lace may be made by folding and stitching a narrow strip of the shirting material; otherwise it may be made of plastic or other semi-stiff and resilient material. The end of the lace 19 opposite end 18 may be suitably stiffened to form a tag 20.

With the rim 5 of turned down portion 3 of the collar inserted in channel 13 that is, with the two portions 2 and 3 of collar 1 in proper position, the tag 20 is passed through the end holes 16 in rim 5 and out through the corresponding hole 15 in flap 12, then back again through the next hole 15, through the corresponding hole 16 and into the hole 14. The tag 20 is now passed along beneath the lining 11 to be brought out through the next hole 14 through 16 then 15. It is then passed back through 15 and the corresponding next series of holes and so back and forth until the lacing has passed right round the collar and the tag 20 has emerged at end 17 (on the left of the drawing) through the end hole 15. A pair 55 of extra holes 21 may be made near this point of

3

exit and in the outside wall of the portion 2, as shown, into which the end of the tag 20 may be passed to be held conveniently out of the way.

With the lacing made as described and completed it is not visible with the shirt worn in the normal manner. The shirt and collar can be washed and laundered as one article and until, due to wear or otherwise, it is desired to replace the turn-down or outer portion 3 no part of the lacing is disturbed. When a change has to be made the tag 20 is withdrawn from holes 21 and the parts are unlaced. The old portion 3 is removed and may be discarded and the new portion 3, Fig. 4, is laced in place. As the collar at fold 4 is probably the only part of the shirt first to wear out the replacement of old portion 3 by a new portion of collar 1 renovates the shirt and makes it fit for further service.

What I claim as new and desire to secure by Letters Patent is:

1. A shirt having a turndown collar, said collar made in two parts the inner or upstanding part of the collar permanently attached to the shirt and having its upper edge divided into outside and inside portions the outside portion having regularly placed lace holes, the turn-down part of the collar folded at its upper edge, said inside turned down edge adapted to fit between the di-

4

vided upper portions of the upstanding part of the collar, lace holes in the folded edge of the collar spaced to correspond with the holes in the outside portion of the upstanding part, and means for removably securing the turned down edge of the collar to the divided upper portion of the upstanding part by a lace passed through the lace holes.

2. A shirt having a turndown collar, said collar made in two parts the inner or upstanding part of the collar permanently attached to the shirt and having its upper edge divided into outside and inside portions the outside portion having regularly placed lace holes, a lining to the inside portion also provided with lace holes, the turn-down part of the collar folded at its upper edge, said inside turned down edge adapted to fit between the divided upper portions of the upstanding part of the collar, lace holes in the folded edge of the collar spaced to correspond with the two sets of holes in the inner lining and in the outside portion of the upstanding part, and means for removably securing the turned down edge of the collar to the divided upper portion of the upstanding part by a lace passed through the lace holes.

HEINZ HENSCHEL.
